UNITED STATES PATENT OFFICE.

PHILIP P. NUNGESSION, OF CLEVELAND, OHIO.

ELECTRIC-ARC LAMP.

SPECIFICATION forming part of Letters Patent No. 297,833, dated April 29, 1884.

Application filed October 4, 1883. (No model.)

To all whom it may concern:

Be it known that I, PHILIP P. NUNGESSION, of Cleveland, in the county of Cuyahoga and State of Ohio, have invented a new and useful Improvement in Electric-Arc Lamps; and I do hereby declare that the following is a full, clear, and exact description of the same.

My invention relates to electric-arc lamps; and it consists of improvements in the details of construction of the parts by which the automatic feed of the movable carbon is maintained, the object being to feed the carbon in more even and uniform manner and by simple mechanism.

15 In the accompanying drawings, Figure 1 represents a section on line $x x$ of Fig. 2. Fig. 2 represents a section of Fig. 1, with parts in side elevation. Figs. 3 and 4 represent details of my invention.

20 The lower carbon is not shown, as only an ordinary fixed carbon is required. The supporting frame-work, being of ordinary construction, is also omitted in the drawings.

The main magnet A A has a tubular case, a , 25 and is wound with a helix, which is in the circuit X. Within it, sliding closely but freely, is a slotted magnet-core of iron, b , copper-plated to prevent oxidizing, which is retained by means of springs 1, and when the magnet 30 becomes energized said armature is drawn up a suitable distance, raising with it the upper carbon. Within the tubular armature is a tube, c , which fits closely, so as to be in frictional contact, but to move freely without the 35 application of much force. This tube c has an adjusting-screw, P, on the top thereof, which regulates the movement of the armature, and thus controls the length of the arc. The carbon-holder C is fixed to this tube, and is raised, 40 when the armature is raised, by the frictional contact of tube c with armature b . The amount of this frictional contact may be regulated in any suitable manner, such as that shown, by a curved friction-plate pressing against the 45 rod c , held in position by an adjusting-screw, or in any well-known manner. Within the tube c is a rod, d , preferably non-magnetic, having a rack-edge, 2, which edge projects through slots in the tube c and tubular armature, and engages with a pinion, e , of a train 50 of gears. This train is moved by pallets ff ,

acting on a ratchet-wheel, F. The pallets, with their retaining-springs, are carried on the ends of arms gg , fixed on a lever, G, pivoted on the axis of the ratchet-wheel. The lever G extends to the temporary magnets H H, and carries an armature, h , by which it is operated, having movement enough to mark the ratchet. The helices of magnets H H are in a shunt, yy' , of the main circuit, around the 55 arc, and these magnets are not affected so long as the carbon points are properly near each other. When, however, the arc becomes too long, the current is shunted into these helices and the armature h is drawn down, thus operating the train of gearing and feeding down the upper carbon. The lever G is provided with a retracting-spring, k , which has an adjusting screw-connection, by means of which it may be set at any desired tension. An 60 insulated spring, l , having platinum point meeting like point on the lever G, forms part of the shunt between the main line and the helices of the magnets H H. The platinum point on the lever is connected to the coils of 65 H H by wire Y Y. An insulated stop, 5, prevents the armature h from coming quite into contact with the magnet. The spring l follows the lever a short distance, allowing movement sufficient to work the lever, but breaks 70 connection before the armature has reached the stop 5.

In operation, undue increase of the arc turns the current through the coils of magnets H by way of wire Y, spring l , points, and wire Y'. 75 Motion of the lever G breaks the connection, and then magnets H, ceasing to act, permit the spring l to draw back the lever G again into contact with point of spring l , and if the carbon has not been fed forward far enough to reduce the arc properly the motion will be 80 repeated. The movement of the train of gearing causes the rod d to advance in the tube c and bear against the carbon-holder, thus pushing it down. Each movement of the pallet is 85 very small, and the feed is consequently very fine. This gives great steadiness to the light. In order to disengage the pinion from the rack, I mount the whole train and its operating-lever in a frame, K, which slides in grooves in 90 the heads of the magnets. The frame may 100 therefore be drawn back far enough to take

the pinion out of gear with the rack, and then the rod may be pushed up and the frame pushed back to its place.

I claim as my invention -

- 5 1. In an electric lamp, an electro-magnet in the main circuit, having a tubular case, *a*, a slotted magnet-core, *b*, a tube, *c*, within the magnet-core, held by frictional contact and carrying the carbon-holder, a rod, *d*, having 10 a rack-edge adapted to the slotted tube and armature, an escapement-wheel, and pallet-connections with a lever and electro-magnet in a shunt, the parts being combined and operating substantially as described.
- 15 2. In combination with the electro-magnet having hollow case, the hollow slotted magnet-core *b* and tube *c*, carrying the carbon-holder, the rod *d*, having rack-edge, the escapement-wheel, lever *G*, and arms *gg*, carrying pallets,

the electro-magnet *H* *H*, armature *h* on lever 20 *G*, shunt-circuit, and platinum points, all substantially as described.

3. In combination with the rack-edge of the feeding-rod of the lamp, the escapement-wheel and pallets, the train of gearing, and the lever 25 carrying an armature acting in the described relation to the shunt-magnet, said escapement-wheel, train of gearing, and lever being carried upon a sliding frame, whereby the gears may be disconnected from the rack, as set 30 forth.

In testimony whereof I have signed my name to this specification in the presence of two subscribing witnesses.

PHILIP P. NUNGESSER.
